UNITED STATES PATENT OFFICE.

JACOB K. DIMMICK, OF PHILADELPHIA, PENNSYLVANIA.

CORE FOR HOLLOW CASTINGS.

No. 922,678.

Specification of Letters Patent.

Patented May 25, 1909.

Application filed August 28, 1908. Serial No. 450,641.

To all whom it may concern:

Be it known that I, JACOB K. DIMMICK, a citizen of the United States, and a resident of the city of Philadelphia, State of Pennsylvania, have invented certain new and useful Improvements in Cores for Hollow Castings, of which the following is a full, clear, and exact disclosure, reference being had to the accompanying drawings, forming a part of this specification.

The principal objects of my invention are to provide a core for use in casting hollow metal bodies, such as pipe, in which suitable passages are provided for permitting the emission of gases, steam, etc. formed during the casting operation, without materially lessening the strength of the core-bar, and to provide a core which will not permit the molten metal to enter the interior of the core-bar.

Other objects of my invention will appear from the following description and the accompanying drawings.

It is well known to those skilled in the art that in casting operations in which a core is used it is necessary to provide passages therein leading to the outside atmosphere, to allow the escape of the gases, steam, etc. generated when the molten metal is poured, for if such passages are not provided, explosions may occur, and unsatisfactory castings may be obtained. In cores heretofore constructed, such passages have been provided only by materially lessening the strength of the core-bar, so that when unusual pressure is applied thereto, such as being dropped, the bar is very likely to be damaged and its further utility impaired; and furthermore, the molten metal may work through the outer covering of the core, and then pass into the interior of the core-bar through the passages, thereby usually destroying the core-bar, and oftentimes the casting. In my improved core, I have entirely removed these objections, and have provided a core in which are suitable passages for the emission of the gases, etc., while the strength of the core-bar is not materially lessened, and in which the influx of the molten metal within the interior of the core-bar is prevented.

In the accompanying drawings, in which similar parts are referred to by similar ref-

erence figures, Figure 1 is a vertical, longitudinal, sectional view of a flask in which is mounted my improved core with the parts 55 thereof shown partly in section; Fig. 2 is a perspective of a modification of the core-bar used in my improved core; Fig. 3 is a reduced entire top plan view of Fig. 1; and Fig. 4 is a reduced sectional view taken on 60 the line 4—4 of Fig. 1.

In Fig. 1, a suitable flask is indicated by 1, having a base 2 to which the main body of the flask is fastened by any suitable means, such as the bolts 3. A top plate 5 is held in 65 position by removable clamps 6—6. 7 indicates the core, which consists of the core-bar 8, about which is wound a covering, which usually consists of a layer of hay rope 9, upon which is placed a layer of mud, shown at 10, 70 which layer, in turn, is covered by a second layer of mud, shown at 11. Any suitable covering may be employed which will leave the flutes upon the core-bar free to allow the passage of the gases, steam, etc. The molding pattern of sand, which forms the exterior surface of the casting, is shown at 12. The core-bar which I have shown in Fig. 1, and a modification of which is shown in Fig. 2, consists of a hollow, cylindrical body, preferably made of iron, upon the cylindrical surface of which are provided flutes 13—13 of suitable depth, to allow of the passage of the gases, etc. While I have shown these flutes as substantially semi-circular grooves, 85 of substantially even depth, and running in parallel straight lines lengthwise of the core-bar, I do not limit myself to such a construction, for it is obvious that the flutes may be channel-shaped or triangular in cross section, 90 or of many other forms which will come within the scope of my invention. It is also obvious that the flutes do not necessarily run in straight lines along the cylindrical surface of the bar, nor that they are parallel, for 95 they may run spirally about the core-bar and in non-parallel lines. It is only necessary that the flutes should be of sufficient depth that the fillets 14—14 be of sufficient height and frequency to support the inner layer of 100 the covering, such as is shown at 9, to prevent the same from filling or obstructing the flutes 13—13.

I have shown the core-bar as being of the

hollow cylindrical type, but it is apparent that it is not necessary that it should be hollow, for it may be solid if desired, and equally well permit the free passage to the air, through the flutes, of the gases, steam, etc., and it is also apparent that the core-bar may be of any desired shape or form suitable to or as required by the core. Means are provided for permitting the easy removal of the core-bar by the eye-bolt 15, to which suitable hoisting apparatus may be attached, which is mounted upon a spider webbing 16 in the upper end of the core-bar, as shown in Fig. 3. A similar spider webbing 17, which also serves to strengthen the core-bar, is provided in the lower end of the core-bar, as shown in Fig. 4. In the top plate 5 is any suitable gate 18, through which the molten metal is poured when the casting operation is being proceeded with.

In the base 2 is provided a socket 19, in which is seated the core 7, and which also serves to accurately center the core and maintain it in such position. The operation of my invention may be briefly described as follows: When the core 7 is placed in position, as shown in Fig. 1, the mold pattern 12 having been prepared, the molten metal is poured into the flask, through the gate 18, and fills the space 20, between the outer surface of the core and the inner surface of the mold pattern, which determine the shape, thickness, etc. of the desired casting. While the molten metal is cooling, gases and steam, vapors, etc. are generated in the sand within the flask and in the covering of the core-bar, for which passages to the outer atmosphere must be provided. The covering of the core-bar, being porous, permits the said gases, steam, vapors, etc. to pass therethrough and enter the vents 13—13, which conduct the same into the atmosphere without the flask. It will therefore be apparent that I have provided an improved core, whereby casting operations may be carried on at a very small expense, inasmuch as I have provided against the breaking of the core-bar and also against its destruction by the influx of the molten metal within its interior, and I have also provided a core-bar which may be used for an indefinite number of times.

Having thus described my invention, what I claim and desire to protect by Letters Patent of the United States is:

1. A core, comprising a flute-vented core-bar and a coating therefor.
2. A core, comprising a core-bar, a coating therefor, and flute vents upon the core-bar inclosed by said coating.
3. In a core for hollow castings, a core-bar having a groove vent upon the body portion thereof.
4. A core, comprising a core-bar, a coating for the body portion of said core-bar, and a

plurality of fluted vents upon the covered surface of the core-bar.

5. In a core, a core-bar having a flute vented surface.

6. A core, comprising a core-bar having a groove vent upon its outer surface, and a coating inclosing said outer surface and said groove.

7. In a core for hollow castings, a core-bar having flute vents upon its exterior surface.

8. In a core for hollow castings, a core-bar having upon its outer surface vent grooves of substantially even depth.

9. In a core for hollow castings, a core-bar having a groove vent upon the exterior surface of its body portion, terminating substantially at the ends of said body portion.

10. A core, comprising a core-bar, a coating for said core-bar, and fluted vents in said core-bar inclosed by said coating.

11. In a core for hollow castings, a cylindrically shaped core-bar having a groove upon the exterior surface of the body portion thereof.

12. In a core for hollow castings, a cylindrically shaped core-bar having a groove upon the exterior surface of the body portion thereof and terminating at the ends thereof.

13. A core, comprising a cylindrically shaped core-bar having flutes upon the exterior surface of the body portion thereof, and a coating inclosing said body portion, and flutes thereon.

14. A core for hollow castings, comprising a core-bar having vents running lengthwise thereof, and a coating substantially inclosing the core-bar but leaving the fluted ends free.

15. In a core for hollow castings, a hollow core-bar, a plurality of flutes running lengthwise upon the exterior surface of said core-bar, and webbings within each end of the core-bar.

16. In a core for hollow castings, a hollow core-bar, a plurality of flutes running lengthwise upon the exterior surface of said core-bar, webbings within each end of the core-bar, and an eye-bolt mounted upon one of said webbings and extending beyond the adjacent end of the core-bar.

17. The combination with a core for hollow castings having a fluted core-bar, of a flask having an opening therein adapted to engage an end of the core-bar and thereby maintain the core in a substantially stationary position.

18. The combination with a core for hollow castings having a fluted core-bar, one end of which terminates in a reduced portion, of a flask having an opening therein adapted to engage said reduced end portion of said core-bar and thereby maintain the core in a substantially stationary position.

19. A core, comprising a fluted core-bar and a coating therefor, said coating consisting of an inner layer of hay rope, an inter-

mediate layer of mud and an outer layer of mud.

20. A core, comprising a fluted core-bar and a coating therefor, said coating consisting of a layer of hay rope and superimposed layers of mud.

In witness whereof, I have hereunto set

my hand this 27th day of August, A. D., 1908.

JACOB K. DIMMICK.
